UNITED STATES PATENT OFFICE.

WILLIAM E. O'HARA, OF OLDFORGE, PENNSYLVANIA.

WATER-CLOSET.

SPECIFICATION forming part of Letters Patent No. 732,955, dated July 7, 1903.

Application filed October 27, 1902. Serial No. 128,935. (No model.)

To all whom it may concern:

Be it known that I, WILLIAM E. O'HARA, a citizen of the United States, residing at Oldforge, in the county of Lackawanna and State of Pennsylvania, have invented a new and useful Water-Closet, of which the following is a specification.

My invention is an improvement in traps for water-closets, and has for its object the construction of a trap which may be conveniently operated and the pipes flushed at the same time.

The further objects and advantages of my construction will be shown by the following specification and by the accompanying drawings, in which—

Figure 1 is a perspective view of my improvement, the front of the bowl and pipe being broken away to show the trap in position. Fig. 2 is a sectional view, the trap being shown in elevation. Fig. 3 is a view of the upper part of the bowl, parts being in section and the pipe from the flushing-tank being in elevation. Fig. 4 is a detail sectional view of the step, the lower part being broken away to show the seat for the spring.

In carrying out my improvement I employ the usual bowl A, flushing-tank B, and the discharge-pipe C. The upper part of the bowl is surrounded by an annular inwardly-projecting flange A'. A pipe B' extends downward from the tank and enters the bowl at the rear and is bent around to the front, passing under the annular flange, and is downwardly open at its front end.

The pipe C has an annular shoulder C' formed therein, and beneath this shoulder rests a valve C², pivoted at C³. The side of the pipe opposite the pivoted side of the valve is cut out, as at C⁴, for a purpose to be hereinafter described. A plate D is secured to the floor on the cut-out side of the pipe and has a heavy coiled vertical spring D' secured thereto. Resting on the spring is a disk D², recessed on its lower surface at D³ to provide a seat for the spring and having an upwardly-extending integral standard D⁴

terminating at its upper end in a step D⁵, the upper face of which is serrated. A rod D⁶ extends from the rear of the step upward and at its upper end is attached to a link D⁷, which in turn operates a valve of the usual construction located at B² in the flushing-pipe B'.

Rigidly secured to and extending from the standard D⁴ is a rod E, which passes through the cut-out portion C⁴ and is then bent upward, its end normally resting beneath and supporting the free edge of the valve C². To keep the opening C⁴ closed, slide-plates E' E² cover the opening and slide with the rod E.

It will be obvious from the drawings that a downward movement of the step D⁵ will open the valve at B² and throw the valve C², the rod E being given a downward and horizontal movement.

Having thus fully described my invention, what I claim as new, and desire to secure by Letters Patent, is—

1. In an attachment of the kind described, the combination with a bowl, of a flushing-pipe, a discharge-pipe, a valve pivoted in the discharge-pipe, said pipe being cut away on one side below the valve, a movable step outside the bowl, a rod extending from the step to the valve, slide-plates covering the opening in the pipe, and means connected to the step for flushing the bowl when the step is depressed.

2. In an attachment of the kind described, the combination with a discharge-pipe, a valve pivoted therein, said pipe being laterally cut away below the valve, sliding plates covering said opening, a rod having one end resting beneath the valve and extending through said opening, a movable step connected to the outer end of the rod, a spring under said step, and means connected to the step for flushing the pipe when the step is depressed.

WILLIAM E. O'HARA.
